UNITED STATES PATENT OFFICE.

HENRY P. WHITE AND LEWIS E. PAYNE, OF KALAMAZOO, MICHIGAN; SAID PAYNE ASSIGNOR TO SAID WHITE.

CONE-PULLEY STRUCTURE.

SPECIFICATION forming part of Letters Patent No. 739,368, dated September 22, 1903.

Application filed November 10, 1902. Serial No. 130,721. (No model.)

To all whom it may concern:

Be it known that we, HENRY P. WHITE and LEWIS E. PAYNE, citizens of the United States, residing at the city of Kalamazoo, in the county of Kalamazoo and State of Michigan, have invented certain new and useful Improvements in Cone-Pulley Structures, of which the following is a specification.

This invention relates to improvements in cone-pulley structures.

The invention is particularly applicable to speed-regulators of the belt-driven cone-pulley type, such as are described and illustrated in the United States Letters Patent to Henry P. White, issued June 24, 1902, No. 703,027, in which the belt is arranged and guided so that its like edges are presented to the corresponding ends of the cone-pulleys; and the invention is illustrated in connection with a machine of that class, although it is adapted for use in other relations.

The objects of the invention are, first, to provide an improved belt-driven cone-pulley structure by which any compensating slip of the belt is prevented; second, to provide an improved idler for belts for use in connection with cone-pulleys which in operation will cause the belt to closely and properly fit upon the cone-pulleys and idlers at every point of its contact-surface.

Further objects will definitely appear in the detailed description to follow.

The objects of this invention are accomplished by the devices and means described in this specification.

The invention is clearly defined and pointed out in the claim.

A structure embodying the features of this invention is fully illustrated in the accompanying drawings, forming a part of this specification, in which—

Figure 1 is a side elevation view of a structure embodying the features of our invention. Fig. 2 is an end elevation view looking from the left of Fig. 1 with the pulleys *b* removed. Fig. 3 is an enlarged detail view showing the structure of one of our idlers, one of said idlers being shown in section on a line corresponding to line 3-3 of Fig. 1 looking in the direction of the little arrows.

In the drawings similar letters of reference refer to similar parts throughout the several views.

Referring to the lettered parts of the drawings, the various parts are supported on a suitable frame *A*. The driven cone *B* is mounted upon a suitable shaft, which also carries the tight and loose pulleys *b*, which represent the medium through which power may be delivered to the machine. A driving-cone *B'* is mounted upon a suitable shaft which is supported at an angle, preferably at right angles, to the shaft of the driven cone *B*. The cones *B* *B'* are arranged so that their like ends occupy the same relative positions toward a common meeting-point of the shafts.

The track or way *A'* is supported by the frame *A*. A carriage *C* is adapted to reciprocate along this track, and suitable means are provided for moving it thereon. On the axle or shaft *C'*, carried by the carriage *C*, are idlers *D*, which are adapted to support and guide the connecting-belt *B'* of said cone. The idlers *D* are cone-shaped and are formed of sections *d*, independently revoluble on the hub *c* of the idler, which is adapted to revolve on the axle *C*.

In a speed-regulator of the class described when belts of any considerable width are used it is found quite necessary to shape them to the pulleys, as the same edge is always presented to the like ends of the pulleys.

In passing over the guide-pulley or idler of the usual construction the belt is subjected to considerable strain, which tends to stretch the same out of shape and weaken it. When a cone-shaped guide-pulley is used, this tendency is overcome; but it is evident that there must of necessity be some compensating slip, as all portions of the belt travel at the same relative speed. In our improved guide-pulley or idler this friction is reduced to a minimum, as the several sections composing the pulley are free to revolve independently, and the belt is guided and presented to the cone in the proper position to reduce the strain thereon to a minimum. By the use of our improved cone-pulley structure

in this relation it is found entirely practical to use a straight belt—that is, a belt without any special shaping, as is otherwise desirable.

We have illustrated and described our improved cone-pulley structure in connection with a speed-regulator. We are aware, however, that it has very great advantages for use in other relations, and therefore desire to claim the same specifically in combination with a speed-regulator, as well as broadly.

Having thus described our invention, what we claim as new, and desire to secure by Letters Patent, is—

The combination of a plurality of independently-revolvable sections of uniformly-increasing diameters, which together unite to form an idler of regular taper, as specified. 15

In testimony whereof we have hereunto set our hands and seals in the presence of two witnesses.

HENRY P. WHITE. [L. S.]
LEWIS E. PAYNE. [L. S.]
